UNITED STATES PATENT OFFICE.

BENJAMIN Q. P. FOSS, OF CHICAGO, ILLINOIS, ASSIGNOR TO FOSS GAS BURNER AND HEATING COMPANY, OF CHICAGO, ILLINOIS, A CORPORATION OF ARIZONA TERRITORY.

GAS-BURNER.

992,181.

Specification of Letters Patent. Patented May 16, 1911.

Application filed July 3, 1909. Serial No. 505,825.

To all whom it may concern:

Be it known that I, BENJAMIN Q. P. Foss, a citizen of the United States, residing at Chicago, in the county of Cook and State of Illinois, have invented certain new and useful Improvements in Gas-Burners, of which the following is a specification.

My invention relates in general to apparatus for generating heat, and more particularly to gas burners.

It is well-known that ordinary illuminating gas possesses advantages over other forms of fuel for generating heat, in that it is smokeless, odorless, and cleanly, as it is piped directly to the place of use, and leaves no ashes. It is also extremely convenient and very accessible at the present time.

While gas burners are now in general practical use for domestic cooking and are used to some extent for locally heating rooms, yet, so far as I am aware, no gas burner has heretofore been produced which enables ordinary illuminating gas at the usual low service pressure to be practically and economically used as a fuel for generating heat on a large scale, such, for instance, as required for bakers' ovens, power plants, factories, heating systems for buildings, etc.

The primary object of my invention is to provide a gas burner which will render it practical and economical to use gas under low pressure, such, for instance, as ordinary illuminating gas at service pressure, for generating the volume and degree of heat necessary for large ovens, power plants, heating systems, and the like.

A still further object of my invention is to provide a gas burner which will be simple in construction, inexpensive in manufacture, and efficient in use.

My invention will be more fully described hereinafter with reference to the accompanying drawings, in which the same is illustrated as embodied in a convenient and practical form, and in which—

Figure 1 is a plan view of my improved burner; Fig. 2, a plan view of one of the combustion chambers detached; Fig. 3, a longitudinal central sectional view through my improved burner; Fig. 4, a cross sectional view on line 4, Fig. 3; and Fig. 5, a cross section on line 5, Fig. 3.

The same reference characters are used to designate the same parts in the several figures of the drawings.

Reference letter A indicates a burner base which is preferably circular, and is provided with a peripheral flange *a*. Projecting from the base A, and preferably located concentrically relatively thereto, is a tubular projection A' through which is adapted to extend a conduit for the supply of gas to the burner. A series of openings A² are formed through the base A, and, preferably, also a series of small holes *a*², such holes being arranged around the tubular projection A', and serve for the passage of air through the base.

Secured to the base A is a frusto-conical chamber B' having a circular opening at its small end, preferably, alining with the tubular projection A'. The chamber B' may be secured to the base A' in any suitable manner, as by means of ears *b*' projecting from its large end and overlying and secured to the flange *a* of the base, screws *c* extending through such ears into engagement with the flange *a*. Four of such ears *b*' spaced equal distances apart are shown, but, of course, the number of such ears is not material.

The outer surface of the chamber B' is provided with lugs C' located adjacent and preferably in alinement with the several ears *b*'. Such lugs C' are provided with recesses *c*' which receive the ears *b*² projecting from a second chamber B². The ears *b*² are secured to the lugs C' by any suitable fastening devices, such, for instance, as screws *c*. The chamber B² is of the same construction as the chamber B', and is provided with lugs C² having seats *c*² therein for receiving ears *b*³ on the third chamber B³, which also is of the same construction as chambers B' and B².

Any number of chambers, such as B', B² and B³, may be in this manner secured together in alinement, three of such chambers having, however, in practice been found sufficient. A fourth chamber B is secured to the chamber B³ by means of ears *b* projecting from the larger end thereof and secured in seats *c*³ formed in the lugs C³ on the chamber B³. The chamber B is also conical, but is provided with a more extended tapered funnel than the other chambers, and is not provided with lugs, inasmuch as the lugs are not necessary, owing to the chamber B being the last one in the series.

The lugs on the several frusto-conical chambers serve not only to connect the adjacent chambers together, but also to space

the chambers apart, thereby forming air supply spaces between the adjacent chambers, such air spaces serving to permit the air to freely pass between the spaced lugs, 5 and thence forwardly between the adjacent conical chambers to the end of the inner of the adjacent chambers.

Extending through the tubular projection A' on the base A is a conduit D for the supply of gas to the burner, such conduit being adjustably secured to the base by means of a clamp screw a' extending through the tubular projection A' into contact with the conduit D. The end of the conduit D is 10 provided with a cap D' having a hole d' extending therethrough, through which the gas is supplied to a point approximately at the center of the first chamber B'.

E indicates a T-coupling, with which is 20 connected a pipe F leading from a source of gas supply, such, for instance, as an illuminating gas service pipe. The flow of gas through the pipe F is controlled by a gate valve f.

If desired, air under pressure may be supplied to the gas before it passes to the burner, in order to increase the pressure at 25 which the gas passes from the conduit D through the opening d' to the interior of the burner.

Reference letter G indicates a pipe for supplying air under pressure located within the gas supply conduit D. The pipe G is provided with a restricted opening g in the 30 end thereof, through which the compressed air is discharged to the interior of the conduit D. The pipe G may be conveniently supported by means of a differential coupling H located in the T-coupling E, as 35 clearly shown in Fig. 3. The end of the pipe G engages within an interiorly screw threaded opening h in the coupling H, while the larger opening of such coupling is engaged by a conduit K for supplying air under 40 pressure from any suitable source, such, for instance, as a tank L. In order to control the flow of compressed air through the conduit H, a valve k, preferably a needle valve, is provided therein.

The manner of using and operation of 45 my improved gas burner are as follows: The burner is located in the desired position to generate heat for the intended purpose. It may be located upon the usual grate of a furnace, or may be either located entirely within an oven, or the discharge end thereof may project within a chamber which is to be heated. The valve f is then operated to 50 permit gas to pass through the conduit D and to be discharged through opening d' into the first chamber B'. The gas is ignited after it passes the opening d'. The escape of the gas through the opening d' creates a suction, thereby drawing air 55 through the openings in the base A which

permits the combustion within the first chamber. The ignited gases then pass through the reduced opening in the chamber B' where additional air is received through the space between the adjacent walls of the 70 chambers B' and B'', thereby further promoting the combustion of the gas. The burning gas then passes successively through the reduced alined ends of the several chambers, and as it passes from the opening in one chamber to that in the next, it is supplied with air through the space between the adjacent chambers. It is thus evident that a plurality of combustion points are provided in my improved burner, owing to the successive supply of air to the gas as it passes to the burner. The gas is consequently completely consumed and in a manner to generate the greatest possible number 80 of heat units.

In some installations of my improved burner, it is desirable to supply compressed air to the gas before it is discharged to the interior of the first chamber, and in such cases the air supply pipe G and communicating conduit K are employed. To permit the discharge of air through the restricted opening g in the pipe G, the valve k is operated so as to place the tank L, or other source of compressed air, in restricted communication with the conduit K.

From the foregoing description, it will be observed that I have invented an improved gas burner, so constructed as to permit the use of gas at low pressure, such as ordinary illuminating gas at the usual low service pressure, for the generating of heat in great volume and at high temperature, thereby enabling the advantages of gas as a fuel for generating heat to be availed of in power plants, bakers' ovens, heating systems, and in other connections in which heretofore it has been impractical to use gas as a heat generating fuel.

While illuminating gas may be conveniently used in my improved burner, yet other forms of combustible gases, such as consumers' gas, or natural gas, may also be efficiently burned therein.

It will be evident that my improved burner is capable of being practically used for other purposes than those heretofore mentioned, such, for instance, as for smelting furnaces, locomotive boilers and marine boilers.

While I have shown and described my invention in its preferred embodiment, it will be understood that it is capable of embodiment in other forms than that herein disclosed, and I, therefore, do not wish to be understood as limiting myself to any specific structural embodiment of my invention, but contemplate embodying the same in any structures coming within the spirit of my claims.

I claim:

1. In a gas burner, the combination with a plurality of alined frusto-conical chambers, of projections on the larger end of each 5 chamber, lugs on the outer surface of each inner chamber to which the projections on the adjacent outer chamber are secured, and a gas supply conduit extending concentrically within the first of said chambers.
- 10 2. In a gas burner, the combination with a base having air supply passages therethrough, of a gas supply conduit extending through and secured to said base, a plurality of alined frusto-conical chambers mounted 15 upon said base, projections on the larger end of each chamber, and lugs on the outer surface of each inner chamber to which the projections on the adjacent outer chamber are secured.
- 20 3. In a gas burner, the combination with a base having air supply openings therethrough, of a frusto-conical chamber secured to said base at its larger end, a plurality of alined frusto-conical chambers mounted 25 upon said first frusto-conical chamber in alinement therewith, means for spacing said chambers apart to form intermediate air supply passages, and means for supplying gas through said base to the interior of said 30 first frusto-conical chamber.
4. In a gas burner, the combination with a base having air supply openings therethrough, of a frusto-conical chamber, the larger end of which is mounted upon said
- base, a plurality of alined frusto-conical 35 chambers mounted upon said first frusto-conical chamber in alinement therewith, means for spacing said chambers apart to form intermediate air supply passages, and a gas supply conduit extending through and 40 adjustably secured to said base.
5. In a gas burner, the combination with a base having air passages therethrough, of a gas supply conduit extending concentrically through and adjustably secured to 45 said base, a plurality of alined frusto-conical chambers mounted upon said base, projections on the larger end of each chamber, and lugs on the outer surface of each inner chamber to which the projections on the adjacent outer chamber are secured. 50
6. In a gas burner, the combination with a base having air supply openings therethrough, of a frusto-conical chamber mounted upon said base at its larger end, a plurality of alined frusto-conical chambers secured to said first chamber in alinement therewith, means for spacing said chambers apart to form intermediate air supply 55 passage, a gas supply conduit extending through said base, and means for supplying compressed air to said gas supply conduit. 60

In testimony whereof, I have subscribed my name.

BENJAMIN Q. P. FOSS.
